Patented Sept. 9, 1975

236,711

SAFETY DEVICE FOR MOTORCYCLE HANDLEBARS

Michael Christopher Burrett, 6376 Fielding Ave.,
Montreal 265, Quebec, Canada

Filed Sept. 27, 1972, Ser. No. 292,508

Claims priority, application Canada Apr. 4, 1972

Term of patent 14 years

Int. Cl. D12—11

U.S. Cl. D12—155

FIG. 1 is a front elevational view of a safety device for motorcycle handlebars showing my new design;

FIG. 2 is a top plan view thereof;

FIG. 3 is a left end elevational view thereof;

FIG. 4 is a right end elevational view thereof; and

FIG. 5 is a rear elevational view thereof.

I claim:

The ornamental design for a safety device for motorcycle handlebars, as shown.
